UNITED STATES PATENT OFFICE.

ARVINE N. THOMAS, OF CANTON, OHIO.

EMBROIDERY-HOOP.

1,078,809.

Specification of Letters Patent. Patented Nov. 18, 1913.

Application filed October 5, 1912. Serial No. 724,149.

To all whom it may concern:

Be it known that I, ARVINE N. THOMAS, a citizen of the United States, residing at Canton, in the county of Stark and State of Ohio, have invented a new and useful Embroidery-Hoop, of which the following is a specification.

My invention relates to improvements in hoops for holding or supporting cloth or other fabric upon which it is desired to embroider designs or do similar work, and particularly relates to that class of embroidery hoops wherein an inner, non-adjustable ring and an outer adjustable ring are provided.

The objects of my invention are to generally improve devices of the character mentioned and to provide a neat, simple, strong, durable and yet easily and cheaply manufactured embroidery hoop having a great range of adjustment and capable of producing thoroughly satisfactory results.

These objects, together with other objects apparent to those skilled in the art, may be attained by the construction illustrated in the accompanying drawings, although the invention may be embodied in other forms, the construction illustrated being chosen by way of example.

In said drawings Figure 1 is a perspective view of an embroidery hoop embodying my invention. Fig. 2 is an enlarged perspective view of a portion of the outer ring including the take-up device. Fig. 3 is a fragmentary, sectional view of the outer and inner rings including the take-up device. Fig. 4 is an inner-side elevation of the take-up lever. Fig. 5 is an elevation of the lever and spring housing of the take-up device.

Throughout the several views similar reference numerals indicate similar parts.

More specifically describing the construction disclosed in said drawings, the numeral 1 indicates generally the inner ring which may be formed of wood, metal or other suitable material and is provided externally with a shallow groove 2 for the reception of the outer ring.

No claim is herein made for the specific construction of the inner ring and further details thereof need not be set forth.

The outer ring is composed of a wire 3 upon which is strung a series of independently rotatable clamping members 4, which are preferably of the round-ended cylindrical form illustrated in the drawings. 55 The wire 3 does not entirely encircle the ring 1, but is provided with the spaced terminal hooks or rings 5 and 6 respectively. The lever and spring housing of the take-up device is formed from a single piece of 60 sheet metal comprising a body 7 formed of a width corresponding to the width of the groove 2 in the inner ring and preferably having a curvature longitudinally adapted to conform to the curvature of said inner 65 ring. Formed integrally with the body 7 are the spaced, parallel outwardly extending flanges 8 provided at one end with the integral lever-fastening lugs 9, which are turned inwardly toward each other, as shown 70 in Fig. 5. Adjacent the end of the housing where the lugs 9 are located a spring-attaching hook 10 is formed by stamping the same out of the body 7 and bending it upwardly from said body intermediate the 75 flanges 8, as clearly shown in the drawings. One end of the extensible coiled spring 11 is connected to said hook 10 and the other end of said spring is connected to the hook 5 of the wire 3, said spring 11 being somewhat shorter than the distance from the hook 10 to the end of the body 7, thus bringing the end of the wire 3 with the first clamping member of the series partially in the end of the housing between the flanges 85 8, as shown in the drawings. The take-up lever is likewise formed from a single piece of sheet metal and comprises the thumb portion 12 and the integral, spaced, parallelly disposed arms 13 provided adjacent their 90 free ends with aligned apertures 14 in which the lugs 9 of the housing are rotatably arranged. One of the arms 13 is provided with an integral wire-fastening lug 15, which is bent over across the space between 95 the arms 13 on the inner side thereof, said lug 15 being arranged intermediate the two ends of the lever. The wire 3 extends between the arms 13 and the hook 6 engages the lug 15, as clearly shown in Figs. 2 and 3. 100

The apertures 14 and thumb portion 12 are arranged in substantially the same general outer line of curvature of the lever, whereas the lug 15, being arranged at the inner edge 5 of the arms 13, is on the inner side of said line of curvature. The take-up lever being connected to the lugs 9, as described, it will be understood that when the thumb portion is moved outwardly and away from the 10 housing the circumference of the outer ring will be increased by reason of the fact that the lug 15 moves through a circular path into a position beyond the end of the housing, whereas, by moving the thumb portion 15 from such extended position back into a position to overlie the housing, as illustrated in Figs. 1 and 3, the lug 15 will be moved into a position intermediate the lugs 9 and the hook 10, thus decreasing the circumference 20 of the outer ring. As the circumference of the outer ring is thus decreased the end clamping member adjacent the lever is drawn up into position to contact with the end of the housing and to protect said 25 clamping member from undue wear, by reason of such contact, a metallic protecting cap 16 is arranged upon the wire 3 and covers the end of said clamping member.

It should be noted that the thumb portion 30 12 is of a sufficient width to overlie the outer edges of the flanges 8 when the take-up device is in the closed or contracted position illustrated in Fig. 3 and the extreme free 35 end of said thumb portion is preferably somewhat narrow and turned down, as shown at 17, so as to extend inwardly between the flanges 8, as shown in Figs. 1 and 3, when the device is in the contracted condition. It will also be noted, by an inspection 40 of Fig. 3, that when the device is in the contracted position there will be no tendency for the take-up lever to move into the extended position for the reason that the lug 15 lies substantially in line with the wire 3, whereas 45 the lugs 9 are arranged outwardly beyond the wire 3. The very tension of the outer ring will thus serve to automatically hold the take-up device in contracted position until such time it is desired to free the 50 outer ring from the inner, whereupon the thumb portion of the take-up lever may be readily grasped and said lever moved into the extended position illustrated in Fig. 2.

By means of the construction illustrated 55 it will be understood that the outer ring of my embroidery hoop may be readily clamped upon cloth or fabric of any thickness arranged upon the inner ring and that, when so clamped, the spring 11 will afford a certain 60 resilient action making it possible to forcibly draw up said cloth or fabric tightly across the inner ring, but preventing said fabric from moving as between said outer

and inner rings except under intentional effort for that purpose on the part of the 65 operator.

I claim:

1. For an embroidery hoop, in combination with an outer ring having spaced ends, a take-up device comprising a housing 70 formed from a single piece of sheet metal and comprising a body portion curved to conform to the curvature of the ring, and spaced flanges extending outwardly from said body, a spring-attaching hook formed 75 on said housing by stamping from the body portion thereof an integral tang extending outwardly between said flanges, an extensible coil spring arranged between said flanges, having one end connected to said hook and the other end connected to one of the ends of said outer ring at one end of said housing, a take-up lever formed from a single piece of sheet metal and comprising a thumb portion and integral, spaced arms 85 pivotally connected to the flanges of said housing at the other end thereof, said lever provided with means for the attachment of the other end of said ring and said other end of said ring extending between said 90 flanges and arms and connected to said ring connecting means intermediate the ends of said lever, said lever being adapted to pivotally move to throw said thumb portion outwardly and away from said flanges to 95 move said ring attaching means away from said coil spring and to move over toward and down upon said flanges to move said ring attaching means toward said coil spring, whereby to move the spaced ends of 100 said ring away from and toward each other, and said thumb portion, when the same engages said flanges, adapted to overlie said spring.

2. For an embroidery hoop, in combination with an outer ring having spaced ends, a take-up device comprising a housing 105 formed from a single piece of sheet metal, and comprising a body portion curved to conform to the curvature of the ring, and spaced flanges extending outwardly from said body, an extensible spring arranged intermediate said flanges and its inner end connected to said housing, the outer end of said spring connected to one end of said ring 110 at one end of the housing, a take-up lever comprising a thumb portion and integral, spaced arms pivotally connected at their free ends to said housing at its other end, the other end of said ring extending between 115 said arms and connected to said lever intermediate its ends, the thumb portion of said lever adapted to move away from said housing into extended position to increase the space between the ends of said ring and toward said housing and into engagement with 120 125

said flanges to decrease said space, said thumb portion terminating at its free end in a narrowed, turned down portion, said thumb portion, when engaging said flanges, adapted to overlie said spring, and said turned down portion adapted to extend between said flanges beyond the outer end of said spring.

In testimony that I claim the above, I have hereunto subscribed my name in the presence of two witnesses.

ARVINE N. THOMAS.
